CLAIM

We claim the ornamental design for a pet feeder with non-skid lower surface, as shown and described.

DESCRIPTION

FIG. 1 is a perspective view of a pet feeder with non-skid lower surface showing my new design;

FIG. 2 is a front elevation view of the pet feeder with non-skid lower surface, the rear and sides being the same;

FIG. 3 is a top plan view; and,

FIG. 4 is a bottom plan view thereof.
